UNITED STATES PATENT OFFICE.

EDWIN E. WAITE, OF FRAMINGHAM, MASSACHUSETTS, ASSIGNOR TO STANDARD WOVEN FABRIC COMPANY, OF FRAMINGHAM, MASSACHUSETTS, A CORPORATION OF MASSACHUSETTS.

BRAKELINING AND SIMILAR MATERIAL.

1,188,588.

Specification of Letters Patent. Patented June 27, 1916.

Application filed December 8, 1914. Serial No. 876,173.

To all whom it may concern:

Be it known that I, EDWIN E. WAITE, a citizen of the United States, residing at Framingham, in the county of Middlesex 5 and State of Massachusetts, have invented certain new and useful Improvements in Brakelinings and Similar Materials, of which the following description, in connection with the accompanying drawings, is a 10 specification, like reference characters on the drawings indicating like parts in the several figures.

This invention relates to brakelinings and similar material designed to be retailed 15 in relatively short lengths and aims to effect an economy in the marketing of materials of this character.

The invention will be readily understood from the following description, reference 20 being made to the accompanying drawing, in which,

Figure 1 is a perspective view of a strip of brakelining embodying this invention; and, Fig. 2 is a similar view on a larger 25 scale of the marginal portion of a short section of this brakelining.

In the drawing, 2 indicates a strip of brakelining wound in a large roll which is the usual form in which this material is delivered to the retailer. The retailer in making a sale measures from the roll a strip of the length required by the customer and cuts it off. The brakelining shown is provided with a series of transverse marks 4 30 which are spaced apart at uniform distances of predetermined length, so that it is merely necessary for the salesman to count the spaces between the marks in order to determine the length of the strip or any given 35 part of the strip between any two of said marks. Since materials of this character are usually sold in lengths of even feet, the marks 4 preferably are spaced apart by intervals of substantially one foot each; that is, it is one foot between the centers of any 40 two adjacent marks. This arrangement not only saves the time and trouble that otherwise would be required in measuring the material for each sale, but also enables the 45 customer to check at a glance the length of strip that he has purchased and determine whether or not the salesman has made a mistake.

Brakelining usually consists of a very hard asbestos fabric impregnated with a 55 composition designed to give it the desired coefficient of friction and then usually baked and calendered. This treatment gives the brakelining a very dark color and makes it 60 very hard and firm. It has been found very 65 difficult to mark the foot prints on the surface of this material in an economical manner and still have them applied in such a way that they will be clear and distinct and will not be obliterated in the handling of 70 the material. An especially difficult problem has been to find a suitable coloring material for making these marks on goods of this character. This difficulty I have solved by using aluminum ink, applying it preferably by running the strip of brakelining 75 between rotary dies of suitable dimension and design; and using sufficient pressure on them to sink or impress the marking members, to which the ink is applied, well into the surface of the material. This operation produces a series of clear, distinct marks impressed in the surface of the goods where there is little danger of rubbing off the ink. The protection of the ink marks in this 80 manner is also of advantage in the process of manufacture, since it permits the rolling of the brakelining up into the form in which it is shipped as fast as it comes through the marking dies and while the ink 85 is still moist and would rub off very easily if it were not for this protection.

Having thus described my invention, what I claim as new and desire to secure by Letters Patent of the United States is: 90

A strip of brakelining of a dark color having a series of transverse aluminum ink marks impressed in its surface and spaced apart at regular intervals of predetermined length, whereby the length of a given portion of said strip between any two of said ink marks can be determined by counting said intervals. 95

In testimony whereof I have affixed my signature, in presence of two witnesses.

EDWIN E. WAITE.
